Primary Examiner — Keith J Wilson(74) *Attorney, Agent, or Firm* — Michael J. Feigin, Esq.; Feigin and Fridman LLC(57) **CLAIM**

The ornamental design for a short distillation head with integrated cooling spiral, as shown and described.

DESCRIPTION

FIG. 1 shows a top and side perspective view of a short distillation head with intergrated cooling spiral of embodiments of the disclosed technology.

FIG. 2 shows a reverse bottom and side perspective view thereof.

FIG. 3 shows a front elevation view thereof.

FIG. 4 shows a side elevation view thereof.

FIG. 5 shows a side elevation view thereof.

FIG. 6 shows a top plan view thereof.

FIG. 7 shows a bottom plan view thereof.

FIG. 8 shows a vertical cross section thereof along section line 8-8 of FIG. 6; and,

FIG. 9 shows a side elevation view thereof with an attached condenser unit.

The short distillation head with integrated cooling spiral is shown with a break to indicate non-specified length. The appearance of any portion of the article between the break lines forms no part of the claimed design.
